UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

LOAD-DISCHARGING CAR.

Application filed July 11, 1924. Serial No. 725,373.

My invention relates to improvements in load discharging cars.

It is an object of my invention to adapt cars having transversely hinged doors to efficiently deposit ballast at the side of the rails and avoid flooding of the same when the doors are opened. Heretofore it has been usual to carry out ballasting operations by means of specially designed cars having doors extending longitudinally of the car which in themselves form deflectors for the load and prevent flooding of the rail, but it has been found that such cars are unusually heavy and furthermore are not well suited for the purpose of carrying other commodities such as coal, thereby entailing a heavy loss to the owners when not in ballasting service.

It is, therefore, a specific object of my invention to adapt a standard type of coal carrying car, by the addition of a comparatively few simple parts, into a car suitable for the discharge and distribution of ballast and to provide means whereby such parts may be conveniently removed from the car when it is desired to withdraw it from ballasting work.

A further object of my invention is to provide a deflector which will automatically position itself, as the door opens, into the path of the discharging load.

My invention also resides in the employment of a dumping door and hopper structure to level off the ballast and in certain other details of construction such as will be pointed out hereinafter.

In the drawings forming a part of this specification, Fig. 1 is a plan view of a portion of a hopper car having my improvements incorporated therewith, the parts being shown in the position assumed when the dumping doors are fully open. Fig. 2 is a vertical longitudinal sectional view of a portion of the car taken on a line corresponding substantially to the section line 2-2 of Fig. 1. Fig. 3 is a transverse sectional view corresponding substantially to the section line 3-3 of Fig. 2, a little more than one-half of the width of the car being disclosed.

In the preferred embodiment of the invention, I have shown my improvements as applied to a hopper car of the type wherein the bottom walls slope longitudinally of the car downwardly from the ends towards

the center of the car, the car having a center-sill surmounted by a central transverse ridge and formed with hoppers, arranged in pairs transversely of the car, but it is obvious that such improvements might be applied in any other desirable situation to accomplish the result intended. As shown each hopper is defined by a longitudinally extending sloping bottom sheet 10, an inner side hopper sheet 11, and outer inwardly sloping side hopper sheet 12 and a part of the usual transverse ridge as indicated at 13. The opening of the hopper is adapted to be closed by a hopper door indicated at 14, the same being hinged to the underside of the ridge sheet 13 by means of the hinge butts 15, thus adapting the door to swing about its upper edge on an axis extending transversely of the car. The two doors of the transversely aligned pair of hoppers in this instance, are adapted to be operated simultaneously and to this end a cross-brace is secured near the free edges of the doors near their lower ends, as indicated at 16, it being understood that said cross-brace passes from one door to the other below, and bridges the space between the center sill construction.

Inasmuch as the construction utilized is the same for both doors of a transversely aligned pair, the description will be confined to a single unit.

In carrying out my invention, I employ a deflecting member 17, which may be of any desired form, either flat or curved in cross section, but preferably consisting of a sheet plate having the sides thereof flanged downwardly as at 18 to provide runners thereon, and for the purpose of imparting stiffness to the said plate. A preferred manner of mounting the said deflecting member on the car structure consists in pivoting one end thereof to the lower edge of the door 14, and supporting the opposite end thereof directly from the stationary floor 10. In carrying out this construction, a pair of hinge brackets 19 are preferably secured to the cross-brace 16 of the door, and a pair of hinge straps 20 are secured to the deflecting member 17 and to the brackets 19 hereinafter described. The pair of hinge straps 20 are spaced apart on the member 17 a sufficient distance to lie between the pair of hinge brackets 19 and thus prevent undue sideways movement of the parts. A rod 21

passes through the hinge brackets 19 and hinge straps 20 and a ferrule 22 is adapted to fill the space intermediate the pair of hinge straps 20 to thereby close the opening 5 between the latter, and prevent leakage of the load when the door is closed. Adjacent the lower edge of each sloping hopper bottom sheet 10 there is provided a stiffening member 23 which is preferably in the form 10 of a Z-bar; said member is provided with a slot 24 through which the deflecting member 17 extends and whereby it is supported in position when the door is opened. While the slotting of a Z member in this manner forms 15 a convenient construction, it will be understood that other constructions may be used, as for instance, a heavy angle iron may be utilized and a hanger of suitable form may depend therefrom to sustain the weight of 20 the said deflector member 17.

When the door is in closed position the deflecting member 17 is adapted to move upwardly to a position beneath the sloping floor and to be there supported by means of a runway 25 preferably formed of a plurality of angle irons 25—25 supported at one end by the stiffening member 23, and at the other end by a stirrup member 26 secured to the sloping sheet 10 and having a horizontal portion secured to and extending between the angle irons 25. Said angle irons 25 are preferably curved as indicated at 27 to facilitate the sliding movement of the deflecting member 17 thereon as the door moves.

35 The opening and closing of the doors is preferably accomplished by means of a device such as illustrated in my prior United States Patent, No. 1,418,907, issued June 6, 1922, inasmuch as this mechanism includes 40 the essentials for opening the door and also for maintaining the same fully open, and limiting the opening movements thereof, thereby permitting the operation of the car as a ballast spreader in either direction and 45 the utilization of the transversely extending door 14 as a leveler for the ballast.

The said operating mechanism utilizes a horizontal operating shaft 28 mounted in suitable bearings 29—29 secured to the 50 hopper structure. Said shaft 28 is extended to one side of the car only, where it is provided with a safety operating device 129 embodying a clutch connection for the purpose of ensuring the safety of the operator 55 on opening the doors. Applied to the shaft 28 at a point thereof beneath the center sill construction is a hub casting 30, said hub casting being rigidly united with the shaft 28 and secured against rotation relatively 60 thereto, and provided with a radially extending arm 31. Operative connection between said arm 31 and the door is effected by means of an elongated link 32, the latter having a pivotal connection as indicated at 33 with 65 said arm, said link being also pivotally

attached to the door. The link 32 is provided with a radial shoulder 34 on its upper side which is adapted to engage with a shoulder forming flange 35, formed on the arm 31, at the end of the full opening movement of the door, to thereby limit the relative swinging movement of the arm 31 and the link 32, the parts in the open position assuming the position indicated by full lines in Fig. 2. 75

The operation of my improved car is as follows: assuming the door is closed and the parts are positioned as indicated in Fig. 2 conventionally by dot and dash lines. The operator rotates the shaft in an counter-clockwise direction as viewed in Fig. 2, and the door opens, drawing the deflecting member 17 outwardly therewith, the onrush of the discharging material assisting the opening movement of the door to its full extent 85 when the pivotal connection 33 will drop slightly below a line passing through the pivotal axis of the pivot connecting link with the door and the center of the shaft 28, thereby automatically locking the door in 90 open position, as will be understood. The discharging material then slopes down from the sides of the deflecting member 17 to either side of the rail 36 and clear thereof, the slopes of such discharging material being 95 shown at 37 and 38, thus leaving ample space for the passage of the wheels 40 of the car without the need of further shovelling. By this construction it will be obvious that the door may be opened to its fullest extent 100 without flooding the rail inasmuch as the member 17 lies directly above the same. With the door fully opened and locked in such position, the car may now be moved forward, and, as movement of the car progresses the ballast is leveled off either by the door 14, or by the stiffening member 23 at the lower edge of the sloping floor sheet 10. If the car is moved in the direction indicated by the arrow 39 the door acts as 110 a leveler being held in its opened position by the mechanism above described and if moved in the opposite direction thereto, the leveling is accomplished by means of the stiffening member 23, and the door in this instance is still maintained in its open position by means of the interengaging shoulders 35 and 34, formed on the arm 31 and link 30 respectively. In this manner a section of roadbed 115 may be ballasted very economically without the use of specially designed cars and when such ballasting operations are concluded, the deflecting members 17 may be entirely removed from the car and conveniently stored until such time as required, and the car in 120 the meantime may be used in the hauling of coal or similar commodities. 125

While I have shown a preferred embodiment of my invention, it is to be understood that the same is susceptible of many modi- 130

fications as for instance in the disposition of the member 17, which may be mounted entirely on the car structure or in various other ways without affecting the result attained, and I wish to claim all constructions coming within the scope of the claims appended hereto.

What I claim is:

1. In a railway car of the W hopper type having transversely hinged doors, a member adapted to be positioned beneath the discharge opening and extending longitudinally of the rail for restricting the extent of door opening and preventing the discharging material from flowing onto the rail.

2. In a railway load-discharging car, the combination with a door opening; of a door hinged transversely of the car, of a deflecting member extending lengthwise of the rail adapted to be disposed in the door opening, said member being disposed above the rail and adapted to deflect the load to either side thereof.

3. In a railway load-discharging car, the combination with a means providing a door opening; of a door; and deflecting means arranged to be automatically disposed in and extended crosswise of the door opening, upon opening of said door.

4. In a railway load-discharging car, the combination with a door opening; of a door; and deflecting means adapted to be disposed in and extended crosswise of the door opening, said means being operable by the movement of said door, and of lesser width than the door opening.

5. In a railway load-discharging car having a dumping opening, a door adapted to close the said opening; and means adapted to deflect the contents of the car exteriorly of the rail, said means being adapted to be moved into the door opening by movement of the door.

6. In a railway load-discharging car, the combination with a hopper defined by a plurality of members, said members meeting at their lower edges; of deflecting means mounted on one of said members and movable therewith; and supporting means for the deflecting means mounted on another of said members.

7. In a hopper car having a sloping hopper bottom sheet and a hopper door pivotally mounted to swing about its upper edge; a deflecting member having one end pivotally mounted adjacent the lower edge of the door, said member extending longitudinally beneath the said sloping hopper bottom sheet; and means carried by the hopper sheet for the purpose of supporting the free end of the deflecting member.

8. In a railway load-discharging car having a hopper, including a movable side and stationary sloping side; a deflecting member pivotally mounted adjacent the free edge

of the movable side and extended inwardly beneath the stationary sloping side; and guideways depending from the stationary floor for the purpose of supporting the said deflecting member.

9. In a railway load discharging car, the combination with a dumping opening; of a door for closing the same, said door having a hinge bracket mounted on the same adjacent the free edge thereof; and a deflecting member pivotally mounted on said hinge bracket, said deflecting member having a portion thereof adapted to be interposed crosswise of the door opening.

10. In a railway load discharging car having a hopper including a movable side and a stationary sloping side, the combination with a deflecting member pivotally mounted adjacent the free edge of the movable side and extended inwardly beneath the stationary sloping side, said deflecting member being provided with runners; of guideways depending from the stationary floor cooperating with said runners for movably supporting the deflecting member, said guideways being formed of a plurality of angles extended upwardly beneath the sloping floor.

11. In a railway load discharging car having a hopper including a movable side and a stationary sloping side; the combination with a stiffening member disposed adjacent the free edge of each of said sides; of a deflecting member having one end thereof pivotally mounted on the stiffening member adjacent the free edge of one of said sides, said deflecting member being extended inwardly beneath the other of said sides and supported thereby by means of the stiffening member adjacent the free edge of the same.

12. In a railway load-discharging car, the combination with means, including a door hinged upon an axis extending transversely of the rail, providing a discharge opening disposed above the rail upon which the car travels; means for deflecting material discharged through said opening away from said rail; and means for leveling said discharged material.

13. In a railway load discharging car, the combination with a door opening of a door hinged transversely of the car adapted to close the same; a deflecting member extending longitudinally of the car adapted for disposition in the door opening; and mechanism adapted to maintain the door in a fixed relation to the door opening whereby the door may be utilized to level the discharged load.

14. In a railway load-discharging car, the combination with means providing an opening disposed above the rail upon which the car travels; of a door pivoted upon a transversely extending axis for closing said opening; means for holding said door in open position; and means for deflecting material

discharge through said opening away from said rail.

15. In a railway load-discharging car, the combination with means providing a discharge opening above the rail upon which the car travels; of a door for closing said opening; means for holding said door in open position; and means operated by movement of said door for deflecting material discharged from said opening.

16. In a railway car having a longitudinally extending center-sill, the combination with hoppers disposed on either side thereof, each said hopper including a sheet sloping longitudinally of the car and a door hinged at its upper end and having the lower edge thereof meeting the lower edge of the sloping floor; of a reinforcing member disposed adjacent the free edge of the sloping floor; a deflecting member extending longitudinally of the car above the rail, said member when the door is opened, being adapted to deflect the material in the car to either side of the rail, said member having one end hingedly mounted at the outer edge of the door and having the opposite end thereto extending through the reinforcing member on the sloping floor; a beam member connecting the doors of the respective hoppers on each side of the center-sill; and mechanism adapted to engage the said beam and maintain the doors in closed position, limit the opening movement of the doors and maintain the same in open position whereby the doors when in open position constitute means for leveling the ballast by the movement of the car in either direction.

17. As an article of manufacture, a deflector for dump cars having a main body portion, provided with pivotal connecting

means adjacent one end thereof, said body portion having runners at the opposite sides thereof.

18. In a railway load discharging car, the combination with means providing a discharge opening above the rail upon which the car travels, said discharge opening including a door adapted to swing on an axis extending transversely of the rail; of a member adapted to be positioned beneath the discharge opening for deflecting the material in the car to either side of the rail during discharge.

19. In a dump car, the combination with a fixed sloping floor portion and a door adapted, when closed, to abut the edge of said sloping floor portion, said door being adapted for swinging movement on an axis extending transversely of the car; of a diverting member positioned beneath the hopper and adapted to extend from the door to the sloping floor portion for the purpose of controlling the flow of material issuing through the discharge opening.

20. In a dump car having a discharge opening and a pivotally mounted door arranged to close the same and so arranged that, normally, the load discharged from said opening forms a pile extended to both sides of and upon the rail therebeneath; load deflecting means movable into position above said rail and extended lengthwise thereof and in the path of discharge of the load adapted to prevent the load being discharged upon the top of the rail.

In witness that I claim the foregoing I have hereunto subscribed my name this 3rd day of July, 1924.

ARGYLE CAMPBELL.
